UNITED STATES PATENT OFFICE

161,061

HOOD ORNAMENT OR SIMILAR ARTICLE FOR MOTOR VEHICLES

John Sneed, Detroit, Mich., assignor to Willis
B. Anderson and Emily A. Anderson, Detroit,
Mich.

Application June 8, 1949, Serial No. 3,129

Term of patent 3½ years

(Cl. D14—18)

To all whom it may concern:

Be it known that I, John Sneed, a citizen of the United States, residing at Detroit, Michigan, have invented a new, original, and ornamental Design for a Hood Ornament or Similar Article for Motor Vehicles, of which the following is a specification, reference being had to the accompanying drawing, forming a part thereof.

Fig. 1 is a side perspective view of a hood ornament or similar article for motor vehicles embodying my invention.

Fig. 2 is a top plan view thereof, the dotted line illustration shown in Fig. 1 having been omitted.

Fig. 3 is a front elevational view thereof, the dotted line illustration shown in Fig. 1 having been partially broken away for convenience of illustration.

The characteristic features of my design reside in the portions shown by means of full lines in the drawing.

I claim:

The ornamental design for a hood ornament or similar article for motor vehicles, substantially as shown and described.

JOHN SNEED.
